LONGITUDINAL JOINT FOR CONCRETE
PAVEMENTS

Ben H. Lampert, Oshkosh, Wis., assignor to Lampert & Lampert, Oshkosh, Wis., a corporation of Wisconsin

Application July 27, 1935, Serial No. 33,427

1 Claim. (Cl. 94—17)

The invention relates to pavements and more particularly to concrete pavements.

In the laying of concrete pavements it has been recognized that cracks will develop in time and that it is important to control the direction of cracking, particularly in the region of the center of the road, and various arrangements have been proposed to provide a weakened plane type of longitudinal joint at the center of the road. The object of the present invention is to provide a joint of the type above described in which vertically disposed metal joint members are readily mounted on a centrally disposed reinforcement and cooperate therewith to provide a weakened plane at the center of the road.

A further object of the invention is to provide a joint construction in which a series of longitudinally extending corrugated sheet metal joint members are detachably secured in vertical position by metal clips to a bar metal reinforcement in the central portion of the pavement.

The invention further consists in the several features hereinafter set forth and more particularly defined by the claim at the conclusion hereof.

In the drawing:

Fig. 1 is a vertical sectional view through the central portion of a concrete pavement having the joint construction embodying the invention; Fig. 2 is a plan view of the parts forming the joint;

Fig. 3 is a detail elevation view of an end of a joint member;

Fig. 4 is a detail sectional view taken on the line 4—4 of Fig. 3;

Fig. 5 is a detail perspective view showing the method and means for connecting the joint members to the bar reinforcement.

Referring to the drawing, the numeral 6 designates generally a concrete pavement which may be of any suitable composition and provided with any suitable or well known reinforcement.

The present invention is designed to provide a weakened plane joint at the central part of any concrete pavement and hence the following description will be confined to this joint which includes a series of interconnected vertically disposed sheet metal joint members 7, a bar support, and means for securing said members to said support.

Each of the joint members 7 is of relatively light gauge sheet metal with longitudinally extending corrugations 8 for strengthening it and also for securing a good bond between said member and the concrete in which it is embedded. These joint members 7 are of a length so that they may be conveniently handled and are

adapted to be connected to each other by an interlocking or slip joint, and for this purpose one end of each joint member 7 has a sheet metal connector part 9 secured thereto as by punchings 10 and having flanged guide portions 11 to slidably receive the end of the next joint member 7, said connector 9 having a hole 12 formed in its body or web so as to provide access to the adjoining ends of the joint members 7. It is also to be noted that the end portions 13 of the corrugated joint members are in line with each other and that the plane passing through said portions forms a base line for the corrugations 8 so that these corrugated portions do not interfere with the slipping of the end joint member into the flanged guide portions 11 of the connector on the adjacent joint member.

The bar support herein shown includes the longitudinally extending reinforcing bars 14 spaced at equal distances from the center line 20 of the concrete pavement and above the subgrade 15 and connected together at intervals by the transversely disposed tie bars 16 which are secured to said bars 14 by tie wires 17.

The joint members 7 are secured in vertically disposed position upon the bar support by metal clips 18 which have oppositely disposed hooked ends 19 and a central portion 20 that straddles the joint member 7 and engages at the bend 21 with the top of said member while holding the bottom edge of said member against one of the transverse tie bars or rods 17 when said hooked ends 19 are hooked onto said bar at opposite sides of said member as shown in Fig. 5.

Thus with the above construction adjacent ends of the joint members 7 are secured together by a slip joint and each member is secured in upright position to the bar reinforcement or support by the clips 18 and this structure when embedded in the concrete pavement as shown in Fig. 1 provides a weakened plane running along the center of the road and designated by the term "Line of fracture".

I desire it to be understood that this invention is not to be limited to any particular form or arrangement of parts except in so far as such limitations are included in the claim.

What I claim as my invention is:

In a longitudinal joint for concrete pavements, the combination of a series of interconnected longitudinally extending sheet metal joint members, a support for said members including spaced tie bars, and clips having a bent portion engaging said members and hooked ends engageable with said bars for securing said joint members in vertically disposed position.

BEN H. LAMPERT.
